ALBERT F. BANCROFT, OF WEST NEWTON, MASSACHUSETTS

DESIGN FOR A SHOE

Application filed November 27, 1931. Serial No. 41,871. Term of patent 3½ years.

To all whom it may concern:

Be it known that I, ALBERT F. BANCROFT, a citizen of the United States, residing at West Newton, in the county of Middlesex and State of Massachusetts, have invented a new, original, and ornamental Design for Shoes, of which the following is a specification, reference being had to the accompanying drawing, forming part thereof.

The figure is a perspective view of a shoe showing my new design.

The dominant feature of the design re-

sides in the ornamental effect produced by a narrow strap, with edges of contrasting colors, which is extended about the edge of the vamp and continued about an opening in the outer side of the upper and is then crossed and knotted and the end extended to one side.

I claim:

The ornamental design for a shoe, as shown and described.

In testimony whereof, I have signed my name to this specification.

ALBERT F. BANCROFT.
